UNITED STATES PATENT OFFICE.

FRANK J. MATCHETTE AND CHARLES MOUKOS, OF MILWAUKEE, WISCONSIN; SAID MOUKOS
ASSIGNOR TO SAID MATCHETTE.

PNEUMATIC BRUSH.

No. 876,371.

Specification of Letters Patent.

Patented Jan. 14, 1906.

Application filed February 16, 1906. Serial No. 301,329.

To all whom it may concern:

Be it known that we, FRANK J. MATCHETTE and CHARLES MOUKOS, a citizen of the United States and a subject of the Kingdom 5 of Greece, respectively, residing at Milwaukee, in the county of Milwaukee and State of Wisconsin, have invented certain new and useful Improvements in Pneumatic Brushes, of which the following is a specification, reference being had to the accompanying drawing, forming a part thereof.

The main object of this invention is to remove dust from walls, ceilings or other finished surfaces, without marking, scratching 15 or marring them.

It consists in certain novel features of construction and in the peculiar arrangement and combinations of parts as hereinafter particularly described and pointed out in the 20 claims.

In the accompanying drawing like characters designate the same parts in the several figures.

Figure 1 is a vertical cross section on the 25 line 1 1, Fig. 3, of a brush embodying the present invention; Fig. 2 is a side elevation of the brush as seen from the left with reference to Figs. 1 and 3 and as provided with an extensible handle, certain parts being broken 30 away; and Fig. 3 is a horizontal section on the line 3 3, Figs. 1 and 2.

For the purpose of illustration a round brush specially designed for cleaning walls and ceilings is shown in the drawing, but the 35 essential features of the invention may be embodied in brushes of other forms, oval, oblong, etc., for different kinds of work or for cleaning surfaces of different kinds.

Referring to the drawing, *a* is the back of 40 the brush, which may be conveniently made as shown in Fig. 1, of wood or similar material in two sections, one fitted within the other. The inner section is provided with bristles *b* and the outer section with one or 45 more rows of bristles *b'*. Between the inner and outer sections a bell-shaped or flaring deflector *c* of rubber, oilcloth or other suitable flexible material is secured. It surrounds the interior bristles *b* and is surrounded and covered by the exterior bristles *b'*, extending from the back towards and terminating short of the free ends of the bristles. The inner back section is formed with a circular

series of downwardly and outwardly inclined openings *d*.

e is a chambered or recessed metal plate attached to the back over the openings *d*. This plate is provided with two hollow socket posts *f*, one of which is made detachable from the plate for the purpose of inserting the 60 handle.

g is a tubular handle detachably secured at one end in a tee *h*, which is fitted to turn in the opposing inner recessed sides of the posts *f*, and is clamped and held therein at any desired angle to the brush back by a screw *i* passing transversely through said posts and the intervening tee and provided at one end with a wing nut *j*. The tee *h* is formed with a split sleeve which is provided with a clamping screw *k* to fasten the handle *g* therein and to facilitate changing one handle for another of different length. The recessed plate *e*, hollow posts *f* and tubular handle *g* form an air and dust conduit which communicates 70 through the openings *d* in the brush back with the interior of the deflector *c*.

The handle may be made as shown in Fig. 2, of tubular sections *g*, so that it can be readily extended by connecting additional sections, each with a coupling sleeve *l*. This coupling sleeve may be permanently attached at one end to one section of the handle and like the tee *h* which connects the handle with the brush, may be split at the other 85 end and provided with a screw *m* for clamping it upon the adjoining end of another section.

In the operation of the brush the tubular handle *g* is connected by a hose with a suction main or air exhausting device, the hose connection or handle being provided with a valve (not shown) and this valve being opened, air is drawn through the openings *d* in the brush back, the recess or chamber in 95 plate *e*, the hollow posts *f*, tubular handle *g*, and the hose and pipe connections and discharged therefrom at any convenient point.

The brush being moved over the surface to be cleaned, the air drawn into and through 100 the bristles is compelled to pass around the free edge of the deflector *c* close to such surface, and to the free ends of the adjacent bristles and the draft is thus concentrated where it will be most effective in aiding the 105 bristles to detach dust and dirt adhering to

said surface and in taking up and carrying away the dust and dirt so detached.

By loosening the nut *j* the brush may be easily turned and set at any desired angle to the handle such as may be most effective and convenient for the particular work to be done. When it is so set it is secured in its adjusted position by tightening said nut. For working on ceilings or walls of different heights the handle is adjusted in length by adding or removing sections, which can be readily accomplished by means of the split coupling sleeves *l*.

In working on polished or finished walls, 15 ceilings or other surfaces with the brush, the outer bristles *b* surrounding the deflector *c*, prevent that deflector from coming in contact with and marking, scratching or defacing such surfaces.

20 Various changes in details of construction and arrangement of parts may be made without departing from the principle and intended scope of the invention.

I claim:

25 1. In a pneumatic brush the combination with the back and bristles, of a flexible deflector surrounding and surrounded by bristles, and an air and dust conduit communicating through the back with the interior of the deflector, substantially as described.

25 2. In a pneumatic brush the combination with the back and bristles, of a deflector surrounding the interior bristles and surrounded by the exterior bristles, and an air and dust conduit communicating with the space inside of the deflector, substantially as described.

30 3. In a pneumatic brush the combination with the back and bristles, of a flexible deflector extending from the back towards the free ends of the bristles surrounding and surrounded by bristles, and an air and dust conduit communicating with the space inside of the deflector, substantially as described.

35 4. In a pneumatic brush the combination with the back and bristles, of a deflector extending from the back towards the free ends of the bristles surrounding and surrounded by bristles, and an extensible tubular handle attached to the back and communicating with the space inside of the deflector, substantially as described.

45 5. In a pneumatic brush the combination with the back and bristles, of a deflector extending from the back towards the free ends of the bristles and surrounded by bristles, and a tubular handle having an adjustable

jointed connection with the back through which it communicates with the space inside 60 of the deflector, substantially as described.

6. In a pneumatic brush the combination with the back and bristles, of socket posts attached to the back, a tubular handle having a tee at one end fitted to turn in said 65 socket posts, and a clamping screw passing through the tee and connecting said posts, one of which is hollow and communicates with an opening through the back, substantially as described. 70

7. In a pneumatic brush the combination with the back provided with bristles and having openings through it, of a chambered plate attached to the back over said openings and provided with hollow socket posts, 75 a tubular handle terminating in a tee which is fitted to turn in said posts and communicates through them with the chamber in said plate, and a clamping screw for fastening said handle at different angles to the back, 80 substantially as described.

8. In a pneumatic brush, the combination with the back and bristles, of a deflector surrounding and surrounded by bristles, a tubular extensible handle communicating with 85 the space inside the deflector and adjustably attached to the back, and means for locking the said handle at various angles relative to the back, substantially as described.

9. In a pneumatic brush, the combination 90 with the back and bristles, of a flexible deflector surrounding and surrounded by bristles, a tubular handle having an adjustable connection with the back in communication with the space inside of the deflector, 95 and adjustable means for locking the handle at various angles to the back, substantially as described.

10. In a pneumatic brush, the combination with the back, provided with bristles and 100 having openings therein, of a chambered plate having hollow socket posts and mounted upon the back over said openings, a deflector surrounding and surrounded by bristles, a tubular handle adjustably connected 105 with said posts and means for locking said handle in adjusted relation to the back, substantially as described.

In testimony whereof we hereto affix our signatures in presence of two witnesses.

FRANK J. MATCHETTE.
CHARLES MOUKOS.
